UNITED STATES PATENT OFFICE

2,271,034

APPLICATOR FOR EYELASH PREPARATIONS
AND THE LIKELeslie Edward Pithie, Upper Hawthorn, Victoria,
AustraliaApplication May 8, 1940, Serial No. 334,033
In Australia March 26, 1940

1 Claim. (Cl. 15—106)

This invention relates to applicators for eyelash, eyebrow and such like preparations.

So far as I am aware the conventional applicator for such preparations is invariably in the form of a brush, resembling a miniature tooth brush but having a single row of comparatively elongated bristles. It is an exceedingly difficult and inconvenient task to apply the preparations with such brush like devices. Even distribution of the preparation over the eyelashes or eyebrows cannot be ensured while there is always a possibility of some of the preparation being wasted.

The present invention seeks to overcome the above and other disadvantages and to this end it contemplates a simple and inexpensive applicator by which preparations of the kind in question may be effectively applied in a most simple, convenient and expeditious manner and without any waste of the preparation.

The above and other objects and advantages of the invention will be readily apparent from the following description aided by reference to the accompanying drawing in which

Figure 1 is a perspective view of an applicator, according to one constructional embodiment, showing how it is used for applying a preparation to eyelashes.

Figure 2 is a perspective view of the applicator of Figure 1.

Figure 3 is a perspective view illustrating an alternative construction.

An applicator according to the invention includes two arms or blades 6 which are interconnected at or adjacent their one ends, and have their free ends 7 normally spaced apart for a suitable distance say about one half an inch (1/2") more or less. Either or both of the arms is (or are) of a resilient nature so that by exerting finger pressure the free ends of the arms may be caused to yieldingly approach each other.

To the free end of each arm is attached a brush element 8. Viewed from the side, these two elements 8 converge outwardly towards each other at an appropriate angle so that when the free ends of the arms 6 are pressed inwardly, the tips or outer end portions of the brush elements come into substantial contact with each other.

In using the improved applicator, an appropriate quantity of a suitable preparation is deposited upon the tips or outer end portions of either or both the brush elements 8 preferably at the inner surfaces thereof. The user or operator then brings the applicator into such position that the eyelashes (or other hairs), to be

treated extend between the two brush elements as indicated in Figure 1. Finger pressure is then applied to the arms to force the two brush elements inwardly so that the tips thereof make substantial contact with each other. In this condition the applicator is moved outwardly so that the preparation is progressively brushed or wiped onto the eyelashes or eyebrows from about the roots to the tips thereof. In this manner the preparation will be uniformly, efficiently and conveniently applied with rapidity and ease, while wastage of the preparation and smudging of the skin of the user therewith will be avoided.

Various constructions may be adopted to give effect to the invention. For example the two arms may be formed separately from spring steel or other suitable resilient material and may be secured together adjacent their one ends by spot welding or by a rivet 9 so that upon relaxation of finger pressure the arms will move apart into the desired comparatively acute V formation of Figure 2.

Each brush element 8 may consist of a single row of bristles 9 the inner ends of which are embedded in a holding strip 11 which is appropriately secured to the free end of the respective arm. For instance, the sides of each backing strip may be provided with grooves or channels 11a and gripped therein by the inturned free end 7 of the respective arm 6 and an end 12a of a clamping jaw 12 that is secured to the respective arm near its free end.

According to an alternative construction illustrated in Figure 3, the arms 6 are formed integral with each other from a single strip of spring steel or other appropriate resilient material.

Having now described my invention what I claim as new and desire to secure by Letters Patent is:

An applicator for eyelash treatment, comprising arms connected at one end and inherently resilient to normally maintain the opposite ends of the arms spaced, a clamping means at each spaced end, and brush elements carried by the clamps, each brush element comprising a relatively wide thin mass of soft, comparatively long bristles arranged wholly in advance of and beyond each arm, the bristles of the respective brush elements inclining toward each other beyond the arms to provide for contact between their free ends and throughout a substantial length toward the arms when said arms are moved toward each other.
